(57) **CLAIM**

The ornamental design for a “box”, as shown and described.

DESCRIPTION

FIG. 1 is a front perspective view of the box;

FIG. 2 is a rear perspective view thereof;

FIG. 3 is a front elevation view thereof;

FIG. 4 is a rear elevation view thereof;

FIG. 5 is a left side elevation view thereof, the other side being mirror-like;

FIG. 6 is a plan view thereof, taken from above; and,

FIG. 7 is a plan view thereof, taken from below.

The broken lines shown in FIGS. 4 and 7 depict environmental structure only and form no part of the claimed design.
